UNITED STATES PATENT OFFICE.

CHARLES W. MCKINLEY, OF TOLEDO, OHIO, ASSIGNOR TO THE WILLYS-OVERLAND COMPANY, OF TOLEDO, OHIO, A CORPORATION OF OHIO.

HOOD-HINGE SUPPORT.

1,346,325.

Specification of Letters Patent.

Patented July 13, 1920.

Application filed October 29, 1917. Serial No. 199,092.

To all whom it may concern:

Be it known that I, CHARLES W. MCKINLEY, a citizen of the United States, residing at Toledo, in the county of Lucas and State 5 of Ohio, have invented certain new and useful Improvements in Hood-Hinge Supports, of which I declare the following to be a full, clear, and exact description.

This invention relates to improvements in 10 motor vehicle hoods, and more particularly to the method of supporting the pintle of the hood hinge relative to the body so that the hood hinge may be adjusted relative to the body.

15 The principal object of this invention is to provide an improved supporting bracket for the pintle of a hood hinge and improved connections between said supporting bracket and the body, whereby the bracket may be 20 universally adjusted relative to the body.

Further objects, and objects relating to economies of manufacture and details of construction, will definitely appear from the detailed description to follow.

25 I accomplish the objects of my invention by the devices and means described in the following specification. My invention is clearly defined and pointed out in the appended claims.

30 A structure constituting a preferred embodiment of my invention is illustrated in the accompanying drawing, forming a part of this specification, in which—

Figure I is a view in side elevation of the 5 forward part of a motor vehicle embodying my invention.

Fig. II is a view partly in plan and partly in section on the line II—II of Fig. III showing a hood hinge supporting bracket constructed in accordance with my invention and connected to the body of a motor vehicle.

Fig. III is a detail, sectional view, taken substantially on the line III—III of Fig. II, and Fig. IV.

Fig. IV is a detail, sectional view, taken substantially on the line IV—IV of Fig. II.

Fig. V is a view, similar to Fig. II, showing a modified form of my invention.

Fig. VI is a detail, sectional view, taken substantially on the line VI—VI of Fig. V.

Fig. VII is a view similar to Fig. II and V, but showing a modified form of my invention.

Fig. VIII is a detail, sectional view, 55 taken substantially on the line VIII—VIII of Fig. IX.

Fig. IX is a detail, sectional view, taken substantially on the line IX—IX of Fig. VII, and

Fig. X is a fragmentary top plan view of 60 the body with the supporting bracket for the hood hinge pintle removed, showing the enlarged opening in said body, through 65 which the stem of the supporting bracket extends.

In the drawings, similar reference numerals refer to similar parts throughout the several views, and the sectional views are taken looking in the direction of the little 70 arrows at the ends of the section lines.

In motor vehicle construction, the hood or casing which covers the engine is usually made up of a plurality of sections, which are connected together by a longitudinally extending hinge, which extends from the top central point of the radiator 75 to the top central point of the cowl. This hinge is provided with a longitudinally extending pintle, one end of which is mounted 80 in a socket provided on the radiator, while the other end is supported from the body, and the whole hood is supported through this longitudinally extending hinge and the 85 pintle thereof.

In carrying out the objects of my invention, I have provided a supporting bracket mounted on the body and having a socket adapted to receive the end of the hinge pintle, which bracket is adjustably mounted on 90 the body so that it may be adjusted in two directions—either longitudinally of the hinge or laterally thereto, so that the hood may be accurately positioned and centered relative to the radiator, the body and the 95 motor vehicle frame.

Considering the numbered parts of the drawings, I have shown the forward part of a motor vehicle, including the frame 10, the radiator 11, the body or cowl 12, and the 100 hood 13. As I have indicated above, the hood is made up of a plurality of sections,

which are connected together by the longitudinally extending hinge 14. The hood sections 13 are provided with the beads 15, which are adapted to overlap the cowl or body 12, at the rear edge of the hood sections. The pintle 16 extends longitudinally through the hinge 14, and the ends of said pintle 16 are supported on the radiator and the body respectively.

Considering Figs. II to IV inclusive, I have shown a supporting bracket for the hinge pintle 16, comprising a plate 17, having a socket 18 therein, which is adapted to receive the ends of the hinge pintle 16. A reinforcing bar 19 is disposed in engagement with the lower surface of the body 12 and extends transversely to the hinge pintle 16, said reinforcing bar being spot-welded at 20 to the body 12. The body is provided with a pair of slots 21, which extend at right angles to the length of the hinge pintle 16, and the reinforcing bar 19 is provided with a pair of slots 22, which are alined with the slots 21 in the body. The central part of the reinforcing bar 19 is struck up as at 23, said struck-up portion 23 extending through an opening 24 in the body. The plate 17 is provided with a pair of slots 25, which extend parallel to the socket 18, and are disposed on opposite sides thereof. The under surface of the plate 17 is provided below the socket 18 with a plurality of grooves 26, which extend parallel to the socket 18, and which are adapted to be engaged by the struck-up portion 23 of the reinforcing bar 19. Bolts 27 extend through the slots 25, 21 and 22, and through openings provided in the bar or strap 29, which is disposed below the reinforcing bar 19. Said bolts are secured in place by the nuts 28 threaded on the ends thereof, whereby the plate 25 is adjustably connected and clamped to the body.

In Figs. V and VI, I have shown a slightly different form of my invention, in which the plate 30 is provided with a socket 18 to receive the pintle 16 of the hinge and is also provided with the slots 25, extending parallel to the socket and disposed on opposite sides thereof. The under surface of the plate 30, however, is not corrugated as in the preferred form of my invention. A reinforcing bar 31 is secured to the under surface of the body 12, and provided with slots 33, which extend at right angles to the slots 25 of the plate 30, and which aline with the slots 21 provided in the body 12. The under surface of the reinforcing bar 31 is provided with the serrations 32, which extend parallel to the socket 18 of the plate 30. A keeper bar 34 is provided having a serrated upper surface adapted to mesh with the serrations 32 of the reinforcing bar 31. Bolts 35 extend through the slots 25, 21 and 33, and through openings provided in the keeper bar

34 and the nuts 36 are threaded on the lower ends of the bolts 35 and clamp the keeper bar with its serrated upper surface in engagement with the serrated lower surface of the reinforcing bar 31. In this manner, the plate 30 is clamped to the body 12, but may be adjusted in two directions relative thereto.

In Figs. VII to X, I have shown a further modification of my invention, in which a plate 37 is provided, having a socket member 38 provided with a socket 39, receiving the pintle 16 of the hinge. An enlarged opening 41 is provided in the body 12 and a stem 40 extends downwards from the plate 37 through the opening 41 and through a smaller opening of substantially the diameter of the stem 40, which is provided in a reinforcing plate 43, disposed in engagement with the lower surface of the body 12. A nut 42 is threaded on the lower end of the stem 40.

From the description of the parts given above, the operation of the device should be very readily understood. Considering the form of my invention shown in Figs. II to IV inclusive, it will be seen that the plate 17 carrying the socket 18 can be adjusted longitudinally of the pintle 16 of the hinge upon loosening the nuts 28 on the bolts 27. During such adjustment the struck-up portion 23 rides in one of the grooves 26. If the nuts 28 are still further unscrewed, the plate 17 may be adjusted laterally with reference to the support upon which it is mounted so that the struck-up portion 23 engages in a different one of the grooves 26. The slots 21 and 25 permit adjustment of the plate 17 in two directions.

The modification of my invention shown in Figs. V and VI, operates in practically the same manner as that shown in Figs. II to IV of the drawing, the complementary engaging serrated surfaces of the reinforcing bar 31 and the keeper bar 34 serving the same purpose as the struck-up portion 23 and the grooves 26 in the other form of my device. In Figs. VII to X inclusive, I have shown a modification of my invention, in which this universal adjustment is effected very easily by providing the plate 37 carrying the pintle socket with the stem 40 extending through the enlarged square opening 41 in the body. The plates 37 and 43 are drawn toward each other by screwing up the nut 42 on the stem 40 so as to clamp between said plate, the edges of the opening 41 but the plate 37 can be instantly adjusted by loosening the nut 42 on the stem 40.

I am aware that the particular embodiment of my invention, which I have here shown and described, is susceptible of considerable variation without departing from the spirit thereof, and, therefore, I desire to

claim the same broadly, as well as specifically, as indicated by the appended claims.

Having thus described my invention, what I claim as new and desire to secure by Letters Patent, is:

1. In a motor vehicle, the combination with a body, of a hood comprising a plurality of sections connected together by a longitudinally extending hinge; and a support 10 for the pintle of said hinge adjustable longitudinally of the pintle and mounted on said body.

2. In a motor vehicle, the combination with a body, of a hood comprising a plurality of sections hinged together by a longitudinally extending hinge; of a support for the pintle of said hinge mounted on said body and adjustable in two directions relative thereto.

3. In a motor vehicle, the combination of 20 a body, of a hood comprising a plurality of sections connected together by a longitudinally extending hinge; of a plate provided with a socket to receive the pintle of said hinge; and means for mounting said plate 25 on said body, whereby the plate may be adjusted relative to the body in two directions.

4. In a motor vehicle, the combination with a body, of a hood comprising a plurality of sections connected together by a longitudinally extending hinge; of a plate provided with a socket to receive the pintle of said hinge, said plate being provided with a pair of slots extending parallel to said socket, said body being provided with a pair 30 of slots extending transversely of said first named slots; and bolts extending through the slots in both the plate and body and adjustably connecting said plate to said body.

5. In a motor vehicle, the combination with a body, of a hood comprising a plurality of sections connected together by a longitudinally extending hinge; of a plate provided with a socket to receive the pintle of said hinge and a pair of slots extending parallel to said socket, said body being provided with a pair of slots extending transversely to the slots in said plate; a reinforcing bar secured to said body and provided with slots 40 aligned with the slots in the body; and bolts passing through the slots in said plate and the slots in said body and reinforcing bar and adjustably connecting said plate to said body.

6. In a motor vehicle, the combination with a body, of a hood comprising a plurality of sections connected together by a longitudinally extending hinge; of a plate provided with a socket adapted to receive the pintle of said hinge, said plate being provided with a pair of slots; a pair of slots being provided in said body, one pair of said slots extending parallel to said socket and the other pair of slots extending at right

angles thereto; and a pair of bolts passing 65 through both the slots in the plate and the body and adjustably connecting the plate to the body.

7. In a motor vehicle, the combination with a body, of a hoop comprising a plurality of sections connected by a longitudinally extending hinge; of a plate provided with a socket adapted to receive the pintle of said hinge, said plate being provided with a pair of slots on either side of said socket 70 and extending parallel thereto, the under side of said plate being provided with a plurality of grooves extending parallel to said socket; a reinforcing bar secured to the body, said body and reinforcing bar being 75 provided with a pair of aligned slots extending at right angles to the slots in the plate, and said reinforcing bar being provided with a struck-up portion adapted to engage in any one of the grooves on the under surface of said plate; a bar provided with a pair of openings therein and bolts extending through the slots in said plate, said body and reinforcing bar, and through the openings in said bar, to adjustably connect said 80 plate to said body.

8. In a motor vehicle, the combination with a body of a hood comprising a plurality of sections connected together by a longitudinally extending hinge; of a plate 95 provided with a socket receiving the pintle of said hinge, and a pair of slots disposed on the opposite sides of said socket and parallel thereto; a reinforcing bar secured to the lower surface of said body, said bar and 100 body being provided with a pair of aligned slots extending at right angles to the slots in said plate, the under surface of said bar being serrated; a keeper bar having an upper serrated surface adapted to engage the 105 serrated surface of said reinforcing bar and provided with a pair of openings; and a pair of bolts extending through said slots and the openings of said keeper bar and adjustably connecting said plate to said body. 110

9. In a motor vehicle, the combination with a body, a hood comprising a plurality of sections connected together by a longitudinally extending hinge; of a plate provided with a socket receiving the pintle of said 115 hinge, said plate being provided with a downwardly extending stem; said body being provided with an enlarged opening through which said stem extends; a plate mounted on said stem and engaging the 120 lower surface of the body; and a nut threaded on said stem and clamping the plate to the body.

10. In a motor vehicle, the combination with a body, of a hood comprising a section 125 mounted upon a longitudinally extending hinge, a support for the pintle of said hinge, means for clamping the support in a plu-

rality of adjusted positions, and additional means for preventing shifting of the support.

11. In a motor vehicle, the combination with a body, of a hood comprising a section mounted upon a longitudinally extending hinge, and a support for the pintle of said hinge mounted on said body and adjustable in two directions relative thereto.
- 10 12. In a motor vehicle, the combination with a body, of a hood comprising a section mounted upon a longitudinally extending hinge, a support for the pintle of said hinge mounted on the body and adjustable longitudinally of the pintle, and coöperating ribbed surfaces for preventing shifting of the support relative to the body.

13. In a motor vehicle, the combination with a body, of a hood comprising a plurality of sections connected together by a longitudinally extended hinge, a support for the pintle of said hinge, and means for clamping the support in a plurality of adjusted positions on the body.

14. In a motor vehicle, the combination of a body, of a hood comprising a section mounted upon a longitudinally extending hinge, a plate provided with a socket to receive the pintle of said hinge, and means for mounting the plate on the body whereby the plate may be adjusted relative to the body in two directions.

In testimony whereof I affix my signature.
CHARLES W. MCKINLEY.
